UNITED STATES PATENT OFFICE.

WILLIAM N. PELOUZE, OF CHICAGO, ILLINOIS.

DESIGN FOR A SCALE-FRAME.

SPECIFICATION forming part of Design No. 33,420, dated October 23, 1900

Application filed March 28, 1898. Serial No. 675,511. Term of patent 14 years.

To all whom it may concern:

Be it known that I, WILLIAM N. PELOUZE, a citizen of the United States, residing at Chicago, in the county of Cook and State of Illinois, have invented and produced a certain new and original Design for a Scale-Frame, of which the following, in connection with the accompanying drawing, is a full, clear, and exact specification.

10 The said drawing is a perspective view of a scale-frame embodying my design.

The leading features of my design consist of a base A, the standard or upright B rising therefrom at one end, the horizontal arm C, 15 the circular disk D, arranged at the end of the arm C, and the strip E, extending from the lower edge of the disk D to the base A. The base A is rectangular, and the standard B is substantially flat and rises substantially 20 vertically therefrom and turns off into the horizontal arm C as though made in one therewith. The dial-disk D is apparently supported by the arm C and the strip E, and it extends slightly above the arm C, as clearly

shown in the drawing. Near the top of the 25 dial-disk D is a vertically-elongated aperture d, and arranged under this and bowed outwardly from the face of the disk D is a perforated loop d'. The arm C, at a point adjacent to the back of the disk D, is provided with a pair of apertures c, between which is a smaller aperture c'. The vertical or upright standard B is provided on each side at a short distance from its outer edge with a flange b, and each of which flanges is provided near its 30 upper and lower ends with perforations b', and the base A is provided at each side with a pair of slots a.

Having thus described my invention, what I claim as new therein, and desire to secure by 40 Letters Patent, is—

The design for a scale-frame substantially as herein shown and described.

WM. N. PELOUZE.
